[57] **CLAIM**

The ornamental design for a portable canine water dispensing and drinking device, as shown and described.

DESCRIPTION

FIG. 1 is a perspective view of the portable canine water dispensing and drinking device showing my new design in the water dispensing and drinking position;

FIG. 2 is a top plan view thereof;

FIG. 3 is a right side elevational view thereof, the left side being a mirror image thereof;

FIG. 4 is a front elevational view thereof;

FIG. 5 is a bottom plan view thereof;

FIG. 6 is a rear elevational view thereof;

FIG. 7 is a perspective view of the portable canine water dispensing and drinking device showing our new design in the folded carrying and storage position;

FIG. 8 is a top plan view of the portable canine water dispensing and drinking device showing my new design in the folded carrying and storage position;

FIG. 9 is a right side elevational view of the portable canine water dispensing and drinking device showing my new design in the folded carrying and storage position and wherein a portion of the drinking pan is broken away to show the nozzle assembly, the left side view being a mirror image of the right side view; and,

FIG. 10 is a sectional view taken along the line 10—10 in FIG. 8.
